QUICK-DETACHABLE MOUNTING FOR JEWELRY
DROP ORNAMENTRalph C. Bangs, Providence, R.I., assignor to Coro, Inc.
of Rhode Island, a corporation of Rhode Island

Filed Apr. 28, 1958, Ser. No. 731,472

1 Claim. (Cl. 63—13)

The present invention relates generally to the jewelry art and is more particularly concerned with a novel and improved mounting means for so-called "drop" ornaments.

A primary object of the instant invention is the provision of means for mounting a "drop" ornament in such a way that the ornament is securely attached when the jewelry article is in wearing position, but whereby the ornament may be readily and simply detached whenever desirable.

Another important object of my invention is the provision of a quick-detachable mounting for "drop" ornaments whereby the ornament may be readily and simply removed for replacement by a different "drop" ornament.

Another object of this invention is the provision of novel and improved mounting means for a "drop" jewelry ornament whereby the versatility of the jewelry product with which said ornament is associated is greatly increased in that the same jewelry article may be readily varied to create different and distinct ornamental impressions and to blend with different ensembles.

A further object of my invention is the provision of a mounting of the character described which may be easily and feasibly associated with a wide variety of jewelry products, such as earrings, brooches, etc., and which may be easily operated and manipulated by the wearer.

Still another object of the present invention is the provision of a quick-detachable mounting for "drop" ornaments which is simple and efficient in operation, economically feasible to manufacture, of durable construction, and of pleasing appearance to the eye.

Other objects, features and advantages of the invention will become apparent as the description thereof proceeds when considered in connection with the accompanying illustrative drawings.

In the drawings which illustrate the best mode presently contemplated by me for carrying out my invention:

FIG. 1 is a front view of an earring embodying the instant invention, the dotted lines showing the ornament in position for detachment;

FIG. 2 is a side elevational view thereof;

FIG. 3 is a rear view thereof;

FIG. 4 is a section, on an enlarged scale, taken on line 4—4 of FIG. 2;

FIG. 5 is a section, on an enlarged scale, taken on line 5—5 of FIG. 1;

FIG. 6 is a perspective detail, on an enlarged scale, of the spherical wall which forms a part of my construction;

FIG. 7 is a perspective detail, on an enlarged scale, of the circular wall which forms a part of the instant construction; and

FIG. 8 is a perspective detail, on an enlarged scale, of the pivotal mounting element which forms a part of my invention.

It has been found desirable to provide a construction whereby a hanging, drop-like ornament may be readily removed from an associated jewelry item for replacement by a different drop ornament. More specifically, although the prior art has evidenced various developments whereby the so-called button-type ornament has been made readily detachable in connection with its associated jewelry product, the problem of making a "drop" ornament readily detachable is a much more difficult one and one which has

2

never been successfully solved heretofore. In the development and manufacture of such a construction, it is essential that the means for detaching the ornament be extremely simple and require no tools or the like, while at the same time it is equally important that the ornament be securely assembled when the jewelry item is in wearing position in order that there will be no likelihood of the ornament becoming inadvertently detached. The instant invention, now to be described, overcomes this problem in a highly unique and ingenious manner.

Referring now to the drawings, there is shown generally at 10 an earring embodying the instant invention. It will be understood, however, that while the drawings illustrate the instant invention as a part of an earring, and while the instant invention is particularly adaptable and advantageous in connection with earrings, the basic principles of this invention are in no way limited to this particular association but rather could be used in combination with a brooch or any other jewelry item having a drop ornament where it is desirable that the ornament be readily detachable for replacement in order that the same jewelry item may be capable of complementing a variety of different ensembles.

Referring to FIG. 2, it will be noted that earring 10 comprises a substantially U-shaped bar 12 having a conventional lobe engaging screw 14 threadedly connected with one extremity thereof as at 16. A semi-spherical housing 18 is secured to the opposite extremity of bar 12 as at 20, it being understood that this securing may be effected by any desirable means, such as soldering or the like.

Referring now to FIGS. 5 through 7, it will be seen that the housing 18 is of hollow construction and comprises a substantially semi-spherical shell 22 and a substantially circular flat wall 24. As will be seen most clearly in FIG. 6, the peripheral edge of shell 22 is provided with an elongated notch 26 terminated at each end by tabs 28, each of which is adjacent to a relatively shallow notch 30. Wall 24, in turn, is provided with a pair of spaced lugs 32 adapted to seat within the aforescribed notches 30 whereby wall 24 is not only prevented from rotating relative to shell 22 when assembled therewith, but also from collapsing inwardly with respect thereto. It will be understood that wall 24 is dimensioned so as to fit snugly within the edge of shell 22, as shown most clearly in FIG. 5, the tabs 28 then being bent over said wall to maintain it in assembled relation (note FIG. 3).

Since the elongated notch 26 is of greater depth than the aforesaid notches 30, it follows that when wall 24 is assembled to shell 22, an elongated slot 34 is provided. If desired, wall 24 may be provided with an integral, outwardly extending tongue 36, said tongue functioning to provide additional soldering surface for receiving the bar 12, as shown most clearly in FIG. 5.

The semi-spherical housing 18 may be of any desired material, although it is preferably of metallic construction, and it will be understood that at least the semi-spherical surface 22 thereof is highly polished or colored to provide a button-like ornament of pleasing appearance. The flat wall 24 thereof is in substantial alignment with the inner end of pressure screw 14 whereupon the wearer's lobe may be gripped therebetween in a manner well known in the art. If desired, a resilient pressure clip of conventional construction could be utilized in place of the screw-type clip illustrated herein without departing from the spirit or scope of this invention.

The means by which a so-called "drop" ornament 38 is detachably associated with earring 10 will now be described. The drop ornament 38, which may be pearl or any other ornamental stone, is mounted in a conventional metallic setting 40 by cementing, clinching, or any other desirable means. The setting or mounting 40 is

in turn provided with an integral eye portion 42 which is adapted to engage over a hook 44 integrally formed at the outer extremity of an elongated mounting element 46. More specifically, element 46 comprises an elongated metallic strap which is pivotally secured to the inner surface of wall 24, as by rivet 43. Aligned apertures 50 and 52 are provided in element 46 and wall 24, respectively, for receiving said rivet, it being important to note that the point of pivotal mounting for element 46 is displaced from the center point of wall 24, or in other words, element 46 is eccentrically mounted with respect thereto.

As will be seen most clearly in FIGS. 4 and 5, element 46 extends outwardly through slot 34 with its hook portion 44 directed toward spherical surface 22. Noting FIG. 5 particularly, it will be seen that when earring 10 is in wearing position with ornament 38 depending straight downwardly, spherical surface 22 functions to block off the open portion of hook 44 whereupon there is no possibility of eye 42 becoming inadvertently disengaged therefrom. Due, however, to the eccentric mounting of element 46, it will be obvious that pivotal movement of said element toward the opposite extremity of slot 44 will cause the hook 44 to move progressively farther away from surface 22 (note FIGS. 1 and 4) whereby the open portion of said hook is no longer blocked and ornament 38 may be readily removed therefrom for replacement by another ornament. Thus, any time a wearer wishes to substitute a different drop ornament for the one presently in use, it is only necessary to pivot the ornament and its mounting element to the opposite end of slot 34 in order to unblock hook 44 whereupon the drop ornament may be readily removed and replaced by another. The whole operation can easily be effected without even removing the earring from the wearer's lobe.

There is very little likelihood of the ornament 38 ever becoming inadvertently disengaged, since when the earring is in its normal wearing position, gravity will tend to maintain mounting element 46 in the position illustrated in FIG. 5, in which position the open portion of hook 44 is effectively blocked. Furthermore, even if element 46 should accidentally pivot from its normal position, it is still unlikely that the ornament would become disengaged from the hook unless physically manipulated to effect such disengagement.

While there is shown and described herein certain specific structure embodying the invention, it will be manifest to those skilled in the art that various modifications and rearrangements of the parts may be made without departing from the spirit and scope of the underlying inventive concept and that the same is not limited to the particular forms herein shown and described except insofar as indicated by the scope of the appended claim. For

5

example, it is not essential that the housing 18 be spherical in configuration, but rather the important thing is that the path of pivotal movement of hook 44 be eccentric to the peripheral edge of housing 18 whereby said hook automatically becomes unblocked during pivotal movement thereof in a given direction.

I claim:

In an earring construction, a mounting bracket, an engaging member joined to one extremity of said mounting bracket for mounting said earring construction on the ear lobe of the wearer, an ornament assembly joined to the other extremity of said mounting bracket, said ornament assembly including a housing that is defined by a substantially semi-spherical ornamental portion that forms the front part of said housing, a flat circular member joined to the rear of said substantially semi-spherical portion and forming the rear wall of said housing, an elongated mounting element pivotally secured to said rear wall in face-to-face relation therewith at a point spaced from the center thereof in eccentric relation and normally extending over a major portion of said wall and projecting beyond the peripheral edge thereof, said mounting element being movable between a first and second position in a plane parallel to the plane of said wall and being formed with a hook on the portion thereof that projects beyond the peripheral edge of said wall, a drop ornament mounted on said hook and being normally securely retained thereon when said mounting element is located in said first position, the end of said hook normally facing in the direction of the substantially semi-spherical portion of said housing so as to be closed by the curvature thereof when said mounting element is in the first position, the eccentric mounting of said mounting element on said wall providing for movement of the end of said hook away from said substantially semi-spherical portion as said mounting element is pivoted from the first or closed position to the second or open position, whereby said hook is accessible for attaching or detaching of said drop ornament.
